4 Claims. (Cl. 29—25.13)

1

The invention relates to a tubular getter container comprising a longitudinal aperture for volatilization of the getter and to a high-vacuum vessel, more particularly an electric discharge tube, provided with such a container. The term "getter" is to be understood to mean a gas absorbing substance.

In high-vacuum vessels general use is made of a gas-absorbing substance, usually barium, which during and after its volatilization absorbs gas residues left in the vacuum vessel. However, since many getters cannot be exposed to air without being attacked, they are frequently introduced into the vacuum vessel within a container shaped into the form of an iron tube, this tube being severed from a long tube filled with the getter, for example barium, and welded to a nickel plate. When the nickel plate, and hence the tube, is being heated in the vacuum vessel the getter evolves at the ends.

Such a container, however, has a disadvantage in that cutting the tube to length must be effected a short time before its introduction into the vacuum vessel, since air is liable to enter through the open ends and bring about slowly proceeding oxidation of the barium, the barium oxide formed often becoming located loosely in the vacuum vessel.

In order to obviate this disadvantage and to enable the getter-filled containers which have been cut to length to be stored in air for any length of time the use of an alloy with aluminium instead of pure getter metal, for example alkaline earth metal, has been contemplated. However, in this case another disadvantage persists in that during the severing operation the ends of the tube are materially narrowed and when welding onto a metal plate or strap the passage for the gas-absorbing metal contained in the tube between the ends may be narrowed or choked.

In a further embodiment of frequent use in which a tube of metal, say, iron is filled with a barium-aluminium alloy and subsequently swaged and drawn out into a wire having an external diameter of, for example, 0.8 mm. and comprising a core of the said alloy 0.5 mm. in diameter, the disadvantages outlined are obviated by grinding off the wall of the iron envelope at one area in the direction of length so as to enable the barium to evolve readily during the heating operation. The wire is then cut into lengths of about 1 cm. after small straps have been welded thereto and this permits of heating by high-frequency currents.

2

The constructions here discussed have a disadvantage in that the issuing jet of vapour exhibits a wide spread, so that the barium vapour is liable to precipitate on a large part of the wall of the vacuum vessel and also on members, such as electrodes, present in this vessel. This is often undesirable in view of insulation and electrode capacities.

In order to give the jet of vapour a definite direction, so that only a small predetermined part of the wall of the vacuum vessel or of an electrode may be covered with a getter mirror, various forms of getter container have already been suggested. Thus, for example, it has been proposed to use a box-shaped getter container provided with a small spout which is kept cool, the getter vapour being thus enabled to issue in a thin jet. However, such a construction is comparatively complicated and unsuited for mass production.

According to the invention, the use of a tubular getter container permits of providing a directional jet of getter vapour in a very simple manner in that with such a getter container, in which the active substance when volatilized is permitted to escape through a longitudinal aperture in the envelope, this aperture is shaped into the form of a narrow slit or slot, through which the getter vapour issues in the form of a directional jet.

This may be effected in various ways. One method starts with a, say, iron or nickel envelope shaped into the form of a tube the external diameter of which is approximately 8 mms. and the wall thickness 1.5 mm., a saw-cut about 1 mm. in width being provided in the wall in the direction of length. Next, the tube is swaged in a rotary swaging machine or otherwise manipulated so as to close the saw-cut and then filled with an alloy of barium and aluminium and subsequently drawn out to an external diameter of, for example, 0.8 mm., the initial saw-cut being found to be again present in the shape of a narrow slit in the iron envelope. Although the wall thickness of the envelope is only about 0.15 mm. the emanating vapour jet on volatilization of the getter, is found to be directed by the side walls of the slit.

In accordance with a further, very suitable method the iron cylinder is not previously provided with a saw-cut, but directly filled with an alloy of the getter substance and then swaged and drawn out to a diameter of, for example, 0.8 mm. The "getter wire" is then passed over a 55 guide wheel above which is arranged a cutting

wheel or a cutter having a V-shaped cutting profile which presses or cuts a V-shaped slot into the envelope. The "getter wire" has then welded on to it, at definite spacings, small U-shaped straps in a given position relative to the slot, the wire being then cut between these straps.

In order that the invention may be more clearly understood and readily carried into effect, it will now be described more fully with reference to the accompanying drawing, in which

Fig. 1 is a sectional view of a known, tubular getter container,

Figs. 2 and 3 are sectional views of tubular getter containers according to the invention,

Fig. 4 is an elevation of such a container mounted on a strap, and

Fig. 5 shows an electric high-vacuum vessel provided with such a getter container.

Referring to the figures, 1 designates the iron envelope, 2 the core constituted by gas-absorbing substance. According to a known embodiment the envelope 1 shown in Fig. 1 is ground so as to be partly flat, almost as far as the active core.

The vapours of the active substance break through the thin part of the envelope and spread practically over an angle of 180°, so that the vapour extends over a large area, which is frequently undesirable.

The iron tube shown in Fig. 2 was initially provided with a saw-cut and after the saw-cut had been closed by swaging it was filled with active substance and drawn out. It is unexpectedly found that subsequent to the drawing operation the slit is again present. Since this slit 6 is circumscribed by substantially parallel walls, the jet of vapour escapes in a sharply defined direction. A jet of vapour escaping from the getter container shown in Fig. 3 exhibits a slightly wider spread. After being drawn out into a wire of the desired diameter this getter container has a V-shaped slot 5 pressed or cut into its envelope. The wire-shaped getter container has then welded to it short, U-shaped straps 6 made, for example, of nickel, about 1 or 2 cms. in width and is severed between the straps. As shown in Fig. 4, the getter container with the strap forms a loop which renders highly effective heating of the getter by high-frequency currents.

The straps provided with a getter container are housed in vacuum vessels, particularly in electric discharge tubes, such that the slit or slot occupies the desired position. As shown in Fig. 5, the use of a getter container according to the invention ensures that the getter precipitates on a very limited area of the tube wall. In the case of small-sized tubes this is very desirable in view of insulation and electrode capacities. Referring to Fig. 5, the getter container 1 together with the strap 6 is secured to a stay pole 11 of an electrode system 10 housed in a bulb 60. The bulb 7 is sealed by means of a bottom 8, which has contact studs 9 sealed in it.

The getter vapour 12 issues in a directional manner from the slit of the container 1, so that a getter mirror is formed only at a small area of the tube wall. The electrode system 10 is consequently not struck by the getter vapour.

and the electrode capacities are practically not affected owing to the small size of the getter mirror.

What we claim is:

1. A method of manufacturing a tubular getter container having a tubular shaped metal envelope partially surrounding the said getter and from which envelope volatilized getter may escape in a directional jet, comprising the steps of forming a longitudinal aperture in a wall of a tubular metal envelope, closing the said aperture, filling the so-closed envelope with a pulverulent getter substance, and drawing the so-filled envelope to reduce the diameter thereof and to cause the said envelope to separate along the line of the said longitudinal aperture.

2. A method of manufacturing a tubular getter container having a tubular shaped metal envelope partially surrounding the said getter and from which envelope volatilized getter may escape in a directional jet, comprising the steps of forming a longitudinal aperture in a wall of a tubular metal envelope, swaging the envelope to close the said aperture, filling the so-swaged envelope with a pulverulent getter substance, and drawing the so-filled envelope to reduce the diameter thereof and to cause the said envelope to separate along the line of the said longitudinal aperture.

3. A method of manufacturing a tubular getter container having a tubular shaped metal envelope partially surrounding the said getter and from which envelope volatilized getter may escape in a directional jet, comprising the steps of forming a longitudinal aperture in a wall of a tubular metal envelope, swaging the envelope to close the said aperture, filling the so-swaged envelope with an alloy of aluminum and alkaline-earth metal, and drawing the so-filled envelope to reduce the diameter thereof and to cause the said envelope to separate along the line of the said longitudinal aperture.

4. A method of manufacturing a tubular getter container having a tubular shaped metal envelope partially surrounding the said getter and from which envelope volatilized getter may escape in a directional jet, comprising the steps of forming a longitudinal aperture about 1 mm. in width in a wall of a tubular envelope having an external diameter of about 8 mms. and a wall thickness of about 1.5 mm., swaging the envelope to close the said aperture, filling the so-swaged envelope with an alloy of aluminum and barium, and drawing the so-filled envelope to an external diameter of about .8 mm. to cause the said envelope to separate along the line of the said longitudinal aperture.
